AWNNG VALANCE BENDING MACHINE HAVING GAUGE MEANS ACTUATED BY CLAMP MEANS

James L. Kovalcik, Johnstown, Pa., assignor to
Winters O. Wendel, Johnstown, Pa.

Application October 7, 1954, Serial No. 460,880

3 Claims. (Cl. 153—46)

The invention relates generally to permanent metal awnings having upper and lower flanged metal strips arranged in alternate layers and supported on transverse runners. This type of awning is well known and at its forward position the strips are usually bent or curved downwardly to form a valance and give the awning a "water fall" front. The purpose of the present invention is to provide a novel and improved apparatus for curving or rolling the valance in the strips.

In awnings of the type shown the upper strips, or pans as they are called in the trade, have downturned flanges on their edges, and the lower strips or pans have upturned edge flanges, and are staggered with respect to the upper pans with the edge flanges of the two layers overlapping. The central portion of both upper and lower pans may be formed with parallel ridges or gutters to improve their appearance. Another object of the present invention is to provide apparatus for rolling the valance in pans of pre-formed contour.

Permanent metal awnings of this type are built to the individual requirements of the customers and must be supplied with a substantial range of variation in the pitch of the top or roof, as well as in the length or projection of the awning from the supporting structure. A further object of this invention is to provide an improved machine for rolling the valance in awning pans varying in pitch over a wide range.

These and related objects are accomplished by the parts, constructions and arrangements comprising the machine of the present invention, a preferred embodiment of which is shown by way of example in the accompanying drawings and described in detail herein. Various modifications and changes in details of construction are comprehended within the scope of the invention as defined in the appended claims.

The present machine comprises generally two parallel contoured bed plates or bottom dies positioned side-by-side, one for an upper pan and one for a lower pan, the dies being curved downwardly at one end on the desired radius for rolling or forming the valance. Hydraulic clamping dies are positioned over the lower dies for clamping straight upper and lower pans in position on the lower dies, and gauges are provided for locating the ends of said pans in proper overhanging relation to the curved ends of the lower dies, the gauges being associated with said clamping dies so as to move out of the way automatically as the clamping dies descend. A hydraulic rolling die assembly is pivoted at the radial center of the curved ends of the lower dies and is rotated about said center by a power operated linkage to roll the valance in said pans, there being a series of selective electric switches operatively associated with the rolling die assembly to control its travel to regulate the angle of the valance.

Referring to the drawings:

Fig. 1 is a fragmentary side elevation of the improved machine comprising the present invention, showing the clamping and rolling dies in raised position.

Fig. 2 is a plan elevation on line 2—2 of Fig. 1, partly broken away.

Fig. 3 is a front elevation with parts broken away and the forwardly extending arms carrying the gauges being shown in section.

Fig. 4 is an enlarged horizontal sectional view, as on line 4—4 of Fig. 1.

Fig. 5 is an enlarged transverse sectional view on line 5—5 of Fig. 1.

10 Fig. 6 is a similarly enlarged transverse sectional view on line 6—6 of Fig. 1.

Fig. 7 is a fragmentary longitudinal sectional view as on line 7—7 of Fig. 5.

15 Fig. 8 is a similar view on a reduced scale, showing the clamping dies lowered and the gauge supporting arms raised.

Fig. 9 is a similar view showing the rolling die assembly after it has been lowered and starting to roll the valance.

20 Fig. 10 is a similar view showing the rolling die assembly at the end of its valance rolling movement.

Fig. 11 is a vertical section of the front end of the lower die bar for the upper pan, taken on line 11—11 of Fig. 5.

25 Fig. 12 is an enlarged fragmentary sectional view on line 12—12 of Fig. 5.

Fig. 13 is an enlarged fragmentary elevation of one of the gauges for positioning the ends of the pans in the machine, as viewed from line 13—13 of Fig. 4.

30 Fig. 14 is an isometric view of one of the lower pre-contoured pans, showing the bend rolled therein by the improved machine to form the valance portion.

Fig. 15 is a similar view of one of the upper pans.

35 Fig. 16 is a similar view of an upper pan having a double bend therein rolled on the improved machine.

Fig. 17 is a perspective view showing a typical awning having upper and lower pans with a front valance portion, such as may be rolled on the present machine.

40 Fig. 18 is a schematic view showing the manner of selectively connecting the series of electric switches to a solenoid valve controlling the rotation of the rolling die assembly to regulate the angle of the valance.

Fig. 19 is a schematic view showing a valve arrangement for operating the clamping and rolling dies in proper sequence.

45 Referring to Figs. 14—17, the strips or pans making up the roof of the awning are arranged in upper and lower tiers or layers and staggered relative to each other. The upper pans are indicated generally at 20 and the lower pans at 21. The upper and lower pans are substantially the same in appearance but are reversely positioned, the upper pans having downturned flanges 22 along their edges for overlapping upturned flanges 23 along the edges of the lower pans.

50 The central portions of the pans are preferably rolled with parallel ribs or gutters 24 and 25, respectively, and with central ridges 26, to improve the appearance of the awning (Fig. 6). Each upper pan has a downturned valance portion 20' at its front end, and each lower pan has a downturned valance portion 21'. The flanges 22 of the upper pans are slightly deeper than the flanges 23 of the lower pans to permit the flanges 22 to contact the gutters 25. Obviously, the bends or curves forming the valance portions must be concentric, so that the flanges 22 of the upper pans along the curve 27 will conform closely to the gutters of the lower pans along the curve 28, when the upper and lower pans are assembled with their flanges overlapping.

55 Louvers 29 may be attached to the sides of the awning, as shown in Fig. 17, but the present invention is not concerned with such louvers.

60 The present improved machine is adapted simultane-

ously to roll the valance portions in one upper pan and one lower pan having the desired contour including the edge flanges 22 and 23 and the ribs and gutters 24 and 25 already formed therein. Moreover, the valances are rolled without scoring or marking the surfaces of the pans in any way, so that the pans may be enameled or otherwise coated before reaching the valance forming machine.

The bottom dies

Referring to Figs. 1-6, the bottom die plate 30 for the upper pan 20 and the bottom die plate 31 for the lower pan 21 are mounted in parallel side-by-side relation at the forward portion of a table top on the machine. The table top consists of a plate 32 supported on laterally spaced vertical side plates 33 connected at a lower level by a horizontal plate 34 and having their front edges connected by a vertical plate 35. As shown the die plate 30 may be made in two parts, the upper plate 30' having the desired contour for fitting in the upper pan 20 and being secured to the lower plate 30 by screws 36.

The die plates 30 and 31 are supported at their side edges in horizontal grooves formed in laterally spaced vertical plates, die 30 being supported on an outer plate 37 and an inner plate 38, and die 31 being supported on an outer plate 39 and an inner plate 40. Preferably, the plate 40 abuts an inner plate 41. The plates 38 and 41 have upwardly extending bracket portions 38' and 41' respectively, for a purpose to be described. The plates 37, 38, 40, 41 and 39 are clamped together by a tie rod 42 having nuts 43 screwed on its outer ends against the outer plates 33 of the table. Spacer sleeves are provided around the rod between the plates to maintain them in proper spaced relation. The spacer sleeve between plates 37 and 38 is indicated at 44 in Fig. 6, the spacer between plates 38 and 41 at 45, and the spacer between plates 39 and 40 at 46.

The clamping dies

The clamping dies 48 and 49 for cooperating with the bottom dies 30' and 31 respectively are secured on the outer ends of a cross bar 50 extending through laterally opposite slots 51 in the bracket portions 38' and 41'. At its central portion the cross bar 50 is connected to the piston rod 52 of a piston 53 (see Fig. 8) vertically reciprocable in a hydraulic cylinder 54. The cylinder has an enlarged base portion 54' secured by screws 55 to a plate 56 resting on the tops of bracket portions 38' and 41', and having laterally extending arms 57. Fluid conduits 58 and 59 connect the upper and lower ends of the cylinder to a hydraulic system for raising and lowering the piston under pressure.

The gauge mechanism

As seen in Fig. 6, the clamping dies 48 and 49 are secured to the undersides of arms 50 by spaced screws 60, and a guide rod 61 extends upwardly from the arm 50 above each of the dies. The lower end of the rods may have heads 62 recessed in the top portions of the dies 48 and 49 and held against the cross arm 50 by the screws 60, with the rods projecting upwardly therefrom through the arm 50 and extending slidably through bushings 62 in the arms 57. The upper ends of the rods 61 have clevises 63 thereon connected to the rear ends of forwardly extending gauge supporting arms 64. The arms 64 have slots 65 through which the pivot pins 66 of the clevises extend.

The arms 64 extend forwardly and then angularly downward, normally terminating at points spaced well in front of the ends of the bottom dies 30 and 31. Laterally extending lugs 68 are secured to the ends of the arms by screw studs 69 (Fig. 4) and gauge bars 70 extend slidably through said lugs horizontally in directions parallel to the bottom dies. Each gauge bar has an offset piece 71 extending downwardly therefrom for abut-

ting the projecting ends of straight upper and lower pans 20 and 21 laid over the dies 30 and 31 prior to bending or rolling the valances. The gauge bars are adjustably secured in the lugs 68 by set screws 72, and as shown in Fig. 13, are provided with graduations for setting the offset pieces at locations corresponding to different valance lengths.

The arms 64 are pivoted adjacent to their rear ends on the legs 73 of a U-shaped bracket 74 secured to the cylinder base portion 54', as best shown in Fig. 4, the pivots being indicated at 75. Thus, when the piston rod 52 is lowered to bring the clamping dies 48 and 49 against pans 20 and 21 laid over the bottom dies 30 and 31, the guide rods 61 automatically pull down on the rear ends of arms 64 and swing their front ends upwardly about the pivots 75, as seen in Figs. 8 and 9, to move the front ends out of the way of the dies which roll the valances in the pans.

At the front ends of the bottom dies are located the curved die blocks around which the pans 20 and 21 are rolled to form the valance portions. The die block 76 abuts the front end of bottom die 30' and is recessed into the side plates 37 and 38 as shown in Fig. 5. The die block 77 abuts the front end of bottom die 31 and is recessed into the side plates 39 and 40. These die blocks have downwardly curved, contoured surfaces 76' and 77' respectively, merging smoothly with the contoured surfaces of the bottom die plates so that the pans can be rolled around the radii of the die blocks while maintaining their pre-formed contour. As best shown in Fig. 11, the bottom dies are set into the die blocks so that the front ends of the dies are tangent to the curved die block surfaces directly above the radial centers of the die blocks.

A shaft 78 is journaled in the die blocks 76 and 77 at the radial centers thereof and extends through the plates 37, 38, 41, 40 and 39. Nuts 79 are screwed on the outer ends of the shaft to clamp the die blocks between the plates, and a bushing 80 is located around the shaft between the plates 38 and 41. The upper edge of the front housing plate 35 of the machine is set into the die blocks at or below the tangent horizontally opposite to the shaft 78.

The rolling die assembly

The construction and mounting of the rolling die assembly is best illustrated in Figs. 4, 5 and 9. It has a frame member 81 journaled on the shaft 78 between the plates 38 and 41 by means of bushing 80, with annular spacer plates 82 and 83 located between the plates and a circular boss 84 on the lower end of member 81. Above the boss 84 the frame member 81 is rectangular in cross section and has a hollow rectangular bore 85 in which a block 86 is slidably mounted, the block being secured to the lower end of the rod 87 which has a piston 88 on its upper end reciprocable in the hydraulic cylinder 89. Cylinder 89 has an enlarged base portion 89' secured by screws 90 to a circular flange 91 formed on top of the member 81. Fluid conduits 92 and 93 connect the upper and lower ends of the cylinder to a hydraulic system for raising and lowering the piston under pressure.

A cross shaft 94 parallel to shaft 78 is secured in the slide block 86, and extends laterally in both directions through vertical slots 95 in member 81. As shown in Figs. 5 and 8, the shaft 94 is directly above the shaft 78 prior to the start of the valance rolling operation. A rectangular slide box or housing fits slidably around the slide block 86 (Figs. 4 and 5) at the slots 95, and is formed by two side plates 96 mounted on the shaft 94, a rear plate 97 secured to the side plates by screws 98 and a front plate 99 secured to the side plates by screws 100. Thus, as the piston rod 87 is reciprocated the shaft 94 is reciprocated in the slots 95, downward movement being limited by the block 86 bottoming in the bore 85.

The upper die plates for rolling the valances on the

pans positioned on the die plates 30 and 31 are carried at the outer ends of shaft 94. These upper die plates comprise a plate 101 having a contour on its undersurface like clamping die plate 48, for cooperating with bottom die plate 30' and die block 76, and a plate 102 having a contour on its undersurface like clamping die plate 49 for cooperating with bottom die plate 31 and die block 77. Referring to Figs. 5 and 6, the die plates 101 and 48 respectively, have die bars 103 and 104 secured to their sides by screws 105 and projecting below the plates for conforming to the side flanges 22 of the upper pans 20. In order to accommodate varying thicknesses of the sheet metal in the pans, the bars 103 and 104 have a slight downward taper and, as shown in Fig. 12, clearance is provided around the screws 105 to allow slight lateral movement of the bars.

The die plates 101 and 102 extend forwardly of the shaft 94 a substantial distance and have laterally projecting ribs 106 extending along their upper edges. The ribs 106 are slidably supported in laterally spaced, vertically disposed plates 107 and 108 also extending forwardly of the shaft 94. Ribs 106 along the inner edges of die plates 101 and 102 are slidably received in longitudinal grooves in inner supporting plates 109 and 110 respectively. The rear ends of plates 109 and 110 are rigidly secured to the cross plate 99 which extends laterally to the outer plates 107 and 108 and has its ends secured thereto. A stop bar 111 is secured to the front ends of inner plates 109 and 110 and extends between the same, and bumper blocks 112 are mounted in the ends of said stop bar for limiting the forward movement of the die plates 101 and 102 in the supporting plates.

Preferably, the shaft 94 has laterally spaced rollers 113 thereon which bear on the upper surfaces of die plates 101 and 102, and small idler rollers 114 may be mounted by studs 115 on the supporting plates 107, 108, 109 and 110 for bearing on the same surfaces. Spacer sleeves around the shaft 94 maintain the rollers 113 in proper position, there being sleeves 116 between the rollers of each pair and sleeves 117 between the inner rollers and the housing side plates 96. The slidable mounting of the die plates 101 and 102 allows the die plates to move relative to their supporting plates, so that as the rolling die assembly swings about the shaft 78, the difference in the amount of arcuate travel of the die plates and supporting plates is compensated for, as indicated in Fig. 9, so that the die plates 101 and 102 do not slide over the surfaces of the pans 20 and 21 and cause scoring or marring thereof.

As previously stated, the frame member 81 on which the rolling die assembly is rotatably mounted is journaled on the shaft 78. As best shown in Figs. 5 and 7, the circular boss 84 on the lower end of member 81 has a projection 118 provided with an angularly projecting ear 119. The ear is pivoted at 120 to a yoke 121 on the upper end of a piston rod 122 reciprocating in a hydraulic cylinder 123 pivotally mounted at its lower end on a bracket 124 supported on the horizontal plate 34 of the machine frame (Fig. 3). As seen in Figs. 8-10, when the piston rod 122 is raised, it swings or rocks the roller die assembly in a clockwise direction about the shaft 78 as a center. The cylinder 123 may be connected to a hydraulic system in a usual manner and the direction of flow through the cylinder controlled by a well-known type of reversing valve which may be solenoid-operated. Means for adjusting the point where the upward movement of the piston is stopped will be described later.

The improved machine is adapted to roll different valances over a range of different angles as regulated by the amount of travel of the rolling die assembly, and each angle of valance has a predetermined length. A series of sizes differing from each other by the same number of degrees, for example 4°, may be adopted and the sizes given consecutive numbers starting with angle of 8° for the No. 1 size, 12° for the No. 2 size, and so on.

The amount of travel of the rolling die assembly determines the angle, and the amount of overhang of the pans beyond the die blocks 76 and 77 determines the length of the valance.

Rolling die controls

Referring to Figs. 3 and 7, a cam shaft 125 is mounted on the front plate 35 of the machine frame by brackets 126, and the shaft has a sprocket 127 driven by a chain 128 from a sprocket 129 keyed on the boss 84 of the rolling die frame member 81. A series of cams 130 is mounted on the shaft 125, one cam for each size number. The cams 130 have projections 131 which are adapted selectively to contact the switch elements 132 of a row of micro-switches supported on an angle bracket 133 on the front plate 35. A size indicator dial 134 is provided on the rear of the table top of the machine, as shown in Fig. 2.

Referring to Fig. 18, the indicator dial 134 is shown electrically connected in circuit between a solenoid 135 for regulating the upward travel of the piston rod 122 which rocks the rolling die assembly, each of the stations or contacts on the dial being electrically connected to the corresponding micro-switches 1 to 14, inclusive. Thus when the operator sets the indicator hand 136 on any of the numbered contacts, that contact is connected by conductor 137 in circuit with the one side of solenoid 135 which operates a valve controlling the travel of piston rod 122. The other side of the solenoid is connected by conductor 139 to one side of each of the microswitches. When the piston rod 122 is raised, the cam shaft 125 will rotate until the micro-switch connected to the solenoid by the indicator hand is closed by its cam and operates the solenoid to stop the piston at the predetermined point.

One method of operating the clamping and rolling dies is shown schematically in Fig. 19, wherein the solenoid 135 is shown operatively connected to a hydraulic reversing valve 140 for operating in proper sequence the pistons actuating the dies, namely, piston 50 actuating the clamping dies, piston 88 actuating the rolling dies radially of the rolling die assembly, and piston 122' attached to piston rod 122 for rocking the rolling die assembly. The valve 140 is supplied with hydraulic fluid under pressure by a reservoir 141 through a pump 142, filter 143 and relief valve 144, and a return line 145 from the reversing valve to the reservoir is connected to the by-pass port of the relief valve.

The forward side of the reversing valve 140 is connected by a conduit 140' with a conventional sequence valve A which is set to open its pressure port at a desired pressure, for example 700 p. s. i. The through passage of valve A is connected to the through passage of a sequence valve B set at 800 p. s. i., which is in turn connected by conduit 146 to one end of the cylinder 54 for actuating piston 50. The pressure controlled by-pass port of valve A is connected by conduit 147 to one end of cylinder 89, and the by-pass port of valve B is connected by conduit 148 to one end of cylinder 123. The opposite end of cylinder 54 is connected by a conduit 149 to the by-pass port of a sequence valve C allowing free flow toward the reservoir but set at 800 p. s. i. for flow in the opposite direction, and the opposite end of cylinder 123 is connected by a conduit 150 to the by-pass port of a sequence valve D allowing free flow toward the reservoir but set at 700 p. s. i. for flow in the opposite direction. The opposite end of cylinder 89 is connected by a conduit 151 to the through passage of valve C. The conduit 152 connecting the through passage of valve C with the reversing valve 140 preferably has a counterbalancing valve E in the line which may be set at 600 p. s. i. to prevent gravity operation of any of the pistons.

When the operator presses the start button 153, solenoid 135 moves the reversing valve 140 to forward position which conducts fluid through conduit 140', valves

A and B, and conduit 146 to lower piston 50 and the clamping dies connected thereto. When piston 50 reaches bottom and pressure thereon builds up to 700 p. s. i., valve A will shift, directing fluid through conduit 147 and lowering piston 88 to lower the rolling die assembly, while holding the set pressure on piston 50. When pressure on piston 88 builds up to 800 p. s. i., valve B will shift, sending fluid to cylinder 123 to rock the rolling die assembly to roll the valances in the pans, while holding the set pressure on piston 88. When the piston 122' has moved to the position pre-selected by the operator by setting the indicator hand 136 at a desired station, solenoid 135 is energized, moving reversing valve 140 to reverse position. This allows oil to be pumped through conduit 152 and valves C and D, and connects conduit 140' with return conduit 145 to first reverse piston 88 and raise the rolling die assembly. Next, valve D operates at 700 p. s. i. to lower piston 122' and return the rolling die assembly to starting position. Then at 800 p. s. i., valve C operates to raise piston 50 and lift the clamping dies. After piston 50 has raised, the fluid passes through relief valve 144, set at 900 p. s. i. for example, into conduit 145 and to the reservoir 141, and the pump can continue to run until the start button is again operated to start another cycle.

An alternative method of controlling the sequence of operations is to utilize a conventional timing mechanism controlling conventional solenoid valves operating each of the cylinders. In such case, the valve for controlling the piston 122' for rocking the rolling die assembly would be a conventional reversing valve having a neutral position, and the valve would be moved to neutral position at the pre-selected position of the assembly, and then to reverse position after the piston 88 is operated to raise the assembly.

Operations

In the operation of the improved machine, the operator sets the indicator hand to the size number required, and then sets the gauges 70 to the same number; the graduations on the gauges 70 having been laid out according to the particular valance lengths corresponding to the several size numbers. That is, the gauge pieces 71 are adjusted in front of the die blocks 76 and 77 the proper distance to give the valance length required. The upper and lower pans 20 and 21 are then placed over the bottom dies 30' and 31 with the outer ends of the pans touching the gauge pieces 71, the upper die plates being in the raised position of Fig. 1.

The operator now presses the start button 153 adjacent to the indicator dial 134 on the table top for operating the hydraulic cylinders 54, 89 and 123 in sequence. First the cylinder 54 is operated to lower the clamping dies 48 and 49, as shown in Fig. 8, automatically swinging the gauges 70 upwardly out of the way, and clamping the pans 20 and 21 in position on the bottom dies 30' and 31. Next the cylinder 89 is operated to lower cross shaft 94 in the slots 95 and clamp the upper die plates 101 and 102 against the pans at the upper tangent points of the die blocks 76 and 77, respectively.

Next, the cylinder 123 is operated to rock the rolling die assembly in a clockwise direction, as indicated in Fig. 9, and as the assembly rocks, the die plates 101 and 102 roll the pans 20 and 21 around the curved surfaces of the die blocks 76 and 77. Due to the difference in arcuate travel of the shaft 94 and the supporting plates 107, 108, 109 and 110 connected thereto, as compared with the arcuate travel of the bottom surfaces of die plates 101 and 102, if the die plates and supporting plates moved as a unit the die plates would slide over the surfaces of the pans as the die plates rocked. However, since the die plates 101 and 102 are free to slide relative to the supporting plates, the die plates can roll the pans around the die blocks without relative surface movement thereon, while the shaft 94 and supporting plates

move ahead a greater arcuate distance. This relative movement is shown in Fig. 9 wherein the bumper 112 on the supporting plate 110 has moved ahead of the die plate 110.

After the rolling die assembly has been rocked to the proper angle, as determined by actuation of the solenoid controlled by closing of the cam-operated micro-switch selected by the indicator 134, reversing valve 140 operates the cylinder 89 to raise the die plates 102 and 103 away from the pans, and the die plates slide downwardly by gravity against the bumpers 112, as shown in Fig. 10. Then the piston 122' operates to rock the rolling die assembly counterclockwise to its original position of Fig. 1, following which the cylinder 54 is operated to raise the clamping dies, whereupon the pans 20 and 21 having the valance portions 20' and 21' formed therein may be removed from the machine. In this connection, the fact that central supports for the clamping dies and the upper die plates are between the dies, permits removal of the pans laterally outward and insertion of straight pans laterally inward, thus conserving time and space as compared with feeding the pans longitudinally into and out of the machine.

If it is desired to form a valance having a double bend as shown in the upper pan 20A in Fig. 16, the front bend 27A is made first in the manner just described, and then the pans are moved forward in the machine a predetermined amount and the operation repeated to form the shallower bend 27B. Referring to Fig. 2, in making the front bend 27A, the operator sets the indicator hand on No. 12 for the first bend and sets the gauges 70 at 12. The upper and lower pans are then inserted as indicated in chain lines with their front ends touching the gauge pieces 71. At this point, the operator places a mark on each pan opposite the lines designated 12 on the table top. The machine is then operated in the manner previously described to perform its cycle and roll the bend 27A in the pans. At the close of the cycle, the operator moves both pans forward until the marks previously placed thereon line up with the front ends of the bottom dies 30' and 31, respectively, moves the indicator hand to No. 13, and again operates the machine. The micro-switch energized by contact No. 13 controls the rolling die assembly to form the bend 27B in the pans. Micro-switch No. 14 is a spare.

In order to form a double bend valance having a greater distance between the front and rear bends, the indicator hand is set at 12 for the first bend, and the pans marked opposite the lines 13. Then after the machine is operated to form the first bend, the pans are moved forward until the marks line up with the front ends of the bottom dies, the indicator hand set at 13, and the second bend formed.

Summary

It will be apparent that the improved machine has a number of advantageous features. An upper pan and a lower pan are rolled simultaneously on one machine and the bends forming the valance portions are concentric so that the upper pans will fit closely around the lower pans when assembled. A large range of sizes having different degrees of bend on the same radius to produce awnings of various pitch can be made easily on the machine, merely by changing the setting of the indicator dial and the length gauges. Because the pans are clamped between contoured dies, and because of the relative movement of the upper die plates in the rolling die assembly, pans which have been previously contoured and enameled or coated may be rolled without distortion and without marring their surfaces. Once the indicator dial and the gauges are set and the pans positioned, the operation is automatic. The central mounting of the dies permits insertion and removal of the pans laterally of the machine.

What is claimed is:

1. A machine for forming valances in contoured

awning pans, comprising a fixed bottom die having a downwardly curved front end around which the valance portion of the pan is formed, a clamping die located rearwardly of said front end, means for operating said clamping die for holding a pan on the bottom die with its front end overhanging the front end of said bottom die, a frame pivotally mounted at the radial center of the front end of said bottom die, a die carrier mounted in the frame for movement toward and away from said bottom die, a gauge located forwardly of said front end in alignment with said bottom die for locating the front end of a pan in overhanging relation to the front end of said die, said gauge lying in the path of movement of said die carrier toward said bottom die, means operatively connecting said gauge with said clamping die for moving the gauge out of said path of die carrier movement upon clamping movement of said clamping die, a rolling die bar carried by said carrier, means slidably mounting said rolling die on said carrier for sliding movement on said carrier tangentially of the front end of said bottom die, means for limiting forward sliding movement, a roller in said carrier engaging said rolling die bar, means for moving said carrier on said frame to cause said roller to press the rolling die against the front end of said bottom die, and for then swinging the frame on its pivot to cause said rolling die bar to roll the overhanging end of the pan around the front end of said bottom die.

2. A machine for forming valances in contoured awning pans, comprising a fixed bottom die having a downwardly curved front end around which the valance portion of the pan is formed, clamping means located rearwardly of said front end and movable toward and away from said bottom die, means to operate said clamping means to hold a pan on said bottom die, a frame pivotally mounted at the radial center of the front end of said bottom die, a die carrier mounted in said frame for movement toward and away from said bottom die, a gauge located forwardly of said bottom die front end in alignment with said bottom die for locating the front end of a pan in overhanging relation to the front end of said die, said gauge lying in the path of movement of said die carrier toward said bottom die, means operatively connecting said gauge with said clamping means for moving the gauge out of the path of die carrier movement upon clamping movement of said clamping means, a rolling die bar, means mounting said rolling die bar on said carrier for sliding movement on said carrier tangentially of the front end of said bottom die, means for limiting forward sliding movement of said rolling die bar, a roller in said carrier engaging said rolling die bar, means for moving said carrier on said frame to cause the roller to press said rolling die bar against the front end of said bottom die, and means for swinging the frame on its pivot to cause said rolling die bar to roll the overhanging end of the pan around the front end of the bottom die.

3. A machine for forming valances simultaneously in an upper channel-shaped awning pan and a complementary inverted lower channel-shaped awning pan, comprising a pair of fixed bottom dies conforming to said upper and lower pans and positioned in laterally spaced side-by-side parallel relation, said dies having laterally aligned downwardly curved coaxial front ends around which the valance portions of the pans are formed, clamping means located rearwardly of said front ends, means for operating 10 said clamping means for holding a pair of pans on the bottom dies with their front ends overhanging the front ends of said bottom dies, a frame pivotally mounted at the radial axis of the front ends of said bottom dies, a die carrier mounted in the frame for movement toward and away from said bottom dies, gauge means located forwardly of said front ends in alignment with said bottom dies for locating the front ends of pans in overhanging relation to the front ends of said dies, said gauge means lying in the path of movement of said die carrier, 15 means operatively connecting said gauge means with said clamping means for moving said gauge means out of said path of die carrier movement, upon operation of said clamping means, rolling die bars on said carrier for mating with the front ends of said bottom dies, means mounting said rolling die bars on said carrier for sliding movement on said carrier tangentially of said front ends, means for limiting forward sliding movement thereof, rollers in said carrier engaging said rolling die bars, means for moving said carrier on said frame to cause said rollers to press the rolling die bars against said front ends, and for then swinging the frame on its pivot to cause said rolling die bars to roll the overhanging ends of said 20 pans around the front ends of said bottom dies.
